UNITED STATES PATENT OFFICE.

ARTHUR WILLIAMS, OF CONNERSVILLE, INDIANA.

PERMUTATION LOCK.

1,412,437.

Specification of Letters Patent. Patented Apr. 11, 1922.

Application filed November 29, 1919. Serial No. 341,383.

To all whom it may concern:

Be it known that I, ARTHUR WILLIAMS, a citizen of the United States, and a resident of Connersville, in the county of Fayette and

5 State of Indiana, have invented certain new and useful Improvements in Permutation Locks, of which the following is a specification.

My invention is an improvement in permutation locks, and has for its object to provide a simple, neat and inexpensive lock of the character specified, capable of use for locking any two parts, one of which fits within the other, and especially adapted to 15 lock in place on a motor vehicle the radiator cap.

In the drawings:

Figure 1 is a front view of the improved lock in place,

20 Figure 2 is a vertical section,

Figure 3 is a section on the line 3—3 of Figure 2,

Figure 4 is a front view of the collar,

Figure 5 is a similar view of the plug,

25 Figure 6 is a perspective view of one of the tumbler rings,

Figure 7 is a view similar to Figure 2 showing a modified construction,

30 Figure 8 is a section on the line 8—8 of Figure 7,

Figure 9 is a front view of the key detached,

Figure 10 is a view similar to Figure 2 showing another embodiment of the invention,

35 Figure 11 is a section on the line 11—11 of Figure 10,

Figure 12 is a view similar to Figure 10 showing another embodiment of the invention,

40 Figure 13 is a section on the line 13—13 of Figure 12,

Figure 14 is a vertical section of another embodiment of the invention,

45 Figure 15 is a section on the line 15—15 of Figure 14,

Figure 16 is a top plan view of one of the locking pins,

50 Figure 17 is a side view with parts in section showing a modified construction.

In the embodiment of the invention shown in Figures 1 to 6 inclusive, the lock is shown in connection with the filling nipple 1 of a radiator 2, the nipple being closed by a plug 3 which screws into the nipple as shown in Figure 2, and has a head 4 which has a

polygonal outline for engagement by a wrench or the like to remove the plug. In the present instance the plug carries a motor meter 5.

60

The upper end of the filling nipple is angularly reduced as shown at 6, and this reduced portion is encircled by three tumbler rings 7, the said rings being alike, and each carrying on its peripheral surface a series 65 of letters, numerals or other characters indicated at 8. The lowermost ring of the series rests upon the shoulder 9 formed between the reduced portion and the body of the filling nipple, and the other rings are 70 supported by this ring and by each other, the topmost ring being flush with the top of the nipple.

The plug 3 has an external vertical groove or keyway 10, and this keyway is adapted to 75 be engaged by locking pins 11 which are mounted to move radially of the nipple 1 in openings which are reamed or counter-bored at their outer ends to receive the heads 12 of the pins.

80 Each ring 7 has an oblong recess 13 on its inner surface, which is adapted to receive the head 12 of the adjacent pin as shown more particularly in Figure 3, when the recess is in register with the head, to permit the pin 85 to move outward far enough to release the inner end thereof from the keyway, to permit the plug to turn.

Referring to Figure 3 it will be noted that the keyway has inclined side walls, having 90 in fact the contour of a gentle curve, and the recess 13 is similarly shaped. The outer ends of the heads 12 of the pin are rounded, so that when a ring 7 is turned, with the parts in the position of Figure 3, the pins 11 95 will be forced inwardly by the engagement of the heads with the ends of the groove 13. On the other hand when the plug 3 is turned with respect to the filling nipple, the pins 11, with the parts in the position of Figure 3, 100 will be forced outwardly, and the plug may turn with respect to the nipple. The rings 7 must be placed in a certain predetermined position with respect to the filling nipple, to bring the grooves 13 in register with the 105 pins, and only one knowing such position, indicated by the characters 8, can so arrange the rings.

In the embodiment of the invention shown in Figures 7, 8 and 9, the filling nipple 14 110 of the radiator 15 is closed by a cap 16 which is threaded on to the nipple, engaging out-

side of the nipple, and the cap carrying the motor meter 17. This cap has an annularly reduced portion 18, near its top, and upon this reduced portion there is arranged a series of tumbler rings 19, similar to the ring 7 of Figure 1.

The periphery of the filling nipple has a flattened surface 20 which forms a locking keyway, for engagement by a key 21 10 pivoted in a vertical recess 22 in the inner face of the cap. This key as shown is angular consisting of two portions extending at an obtuse angle with respect to each other, and the key is adapted to be engaged within 15 the keyway 20 when the rings 19 are turned in the proper positions, and to be released so that it may be swung outward by the turning of the cap with respect to the nipple when the rings are in certain predetermined positions 20 with respect to the other parts.

Each ring 19 has on its inner surface an oblong groove 23 whose ends are inclined as shown in Figure 8, and it will be evident that when these grooves are in register with the 25 key 21, the said key may swing outward to release it from the keyway 20.

In Figures 10 and 11, the lock is shown in connection with a filling nipple 24, which is closed by a cap consisting of a ring or collar 25 and a plug 26 which is rotatable within the collar and also movable longitudinally thereof within limits. The collar 25 is hinged to the filling nipple as indicated at 27, to swing into or out of closing position as 30 indicated in full and dotted lines in Figure 10. A series of tumbler rings 28 is mounted on the reduced upper end of the collar, and these rings operate locking pins 29 in the same manner as in the construction shown 35 in Figures 1 to 6, the pins engaging a keyway in the plug 26, to lock the plug against rotation with respect to the collar.

The lower end of the plug extends below the lower end of the collar, and is provided 40 with oppositely arranged circumferentially extending ribs or lugs 30, which are preferably slightly inclined or spiral. These ribs are adapted to engage beneath similarly shaped ribs 31 on the inner surface of the 45 filling nipple 24 to lock the cap to the filling nipple. Because of the spiral arrangement of the ribs 30-31 the cap will be drawn tightly down on to the filling nipple, and it will be locked against reverse movement by 50 the locking pins which are controlled by the tumbler rings.

In Figures 12 and 13 there is shown a construction wherein the plug 32 fits directly into the filling nipple 33. The upper end of 55 the filling nipple is annularly reduced to receive tumbler rings 34, which control locking pins, not shown, in the same manner as they are controlled in Figures 1 and 2. At its lower end the plug has a reduced portion 65 as shown, which is provided with cir-

cumferentially extending ribs 35, similar to the ribs 30 of Figure 10, and adapted to engage beneath ribs 36 on the inner face of the filling nipple. The ribs 30-31 and 35-36, are oppositely arranged, and are 70 90° or less in length, so that when the ribs 30-35 are out of register with the ribs 31-36 respectively, the ribs will pass each other to permit the plug to move out of the nipple. The ribs 30 of Figure 10 are on the 75 reduced lower end of the plug, and the ribs 35-36 are spiral or inclined for the same purpose as the ribs 30-31.

In Figures 14 and 15 the same arrangement is shown for locking the ignition. In 80 this arrangement the collar 37, which corresponds to the filling nipple of the constructions just described is rigidly secured to the instrument board 38, in such manner that it cannot be removed from the outside. 85 The upper end of the collar is reduced to receive tumbler rings 39 which operate the locking pins 40 mounted in the same manner and controlled by the locking rings in the same manner as in the construction of Figures 1 and 2. The plug 41 has keyways 90° apart as shown in Figure 15 for receiving the pins, so that the plug may be locked in two positions. The plug has threaded engagement with the collar as shown, and at 95 its inner end it contacts with the terminals of the ignition circuit 42 to close said circuit. It will be noticed that the inner end of the plug has nipples or buttons 43 for engaging the terminals, and the two keyways 100 permit the plug to be locked in open or closed position.

The operation of all the devices is practically the same. Only those authorized know what characters on the locking rings 105 must be brought into vertical alinement at a predetermined point, to insure that the grooves of the locking rings will permit the locking pins or the locking key, as the case may be, to move outward, to release the two 110 parts which turn with respect to each other. The improved lock is simple, inexpensive, has no key to become lost, and is always in place, ready for duty.

It will be understood that if desired a ball 115 may be used instead of a locking pin, such a ball as is used for instance in ball bearings. With this construction the holes in the collar instead of being bored or counter-bored to receive the larger end of the locking 120 pin would be reamed with a conical tool, so that the ball could engage the keyway in the plug, but could not drop completely through the hole in the collar.

In the embodiment of the invention shown 125 in Figure 17 the construction is the same as that shown in Figure 1, with the exception that balls are used for the locking means instead of locking pins. In this construction, the plug 44 screws into the nipple 45, 130

and the nipple is encircled by the tumbler rings 46, corresponding to the rings 7 of Figure 1. The plug has an external vertical groove or keyway 47, which is adapted 5 to be engaged by the locking balls 48, the said balls being mounted to move radially of the nipple in the same manner as the pins. The tumbler rings have recesses 49 on their inner faces for receiving the balls when in 10 unlocking position.

It will be understood that the lock is a multiple lock, each tumbler ring, except in the construction of Figure 7, and its locking pin or ball is a lock, operating independently 15 of the other rings, their balls and pins, so far as the function of locking is concerned. The lock in its simplest form consists of the locking means mounted to move radially of one of the telescoping elements, 20 the other of the said elements having a recess for engagement by the locking means, together with the tumbler ring having also a recess for receiving the locking means, the said locking means being controlled to locking 25 movement by the ring, and to unlocking movement by the rotation of the elements with respect to each other.

I claim:

1. In combination with elements fitting 30 one within the other and rotatable with respect to each other, said elements being movable with respect to each other longitudi-

nally when in a predetermined angular position, and releasable means in connection with the elements for preventing such angular movement, said means being controllable from outside the elements, and comprising radially movable locking pins and tumbler rings for moving said pins in one direction, the innermost of said elements having a 35 keyway and the tumbler rings having grooves for engagement by the pins to permit said pins to release the keyway or the tumbler rings, said rings being rotatable on the said outermost element. 40

2. The combination with a screw cap and a tubular member arranged to be closed by said screw cap, of means for locking said cap and said tubular member together, and a plurality of rings rotatable about said 45 screw cap and forming combination means for actuating said locking means.

3. The combination with a tubular member and a closure cap having an attaching portion provided with a groove, locking pins 50 slidable through said tubular member and into said groove, said pins being provided with rounded heads, annuli rotatably surrounding said tubular member and having grooves receiving said rounded heads, the 55 ends of said second named grooves being inclined for urging said pins inwardly as the annuli are rotated.

ARTHUR WILLIAMS.
